UNITED STATES PATENT OFFICE

JAMES W. INGLETON, OF ASTORIA, OREGON

DEVICE FOR GASIFYING HEAVY OILS

Application filed June 10, 1926. Serial No. 114,985.

The invention relates to new and useful improvements in devices for gasifying heavy oils, and more particularly to a device wherein a portion of the heavy oil is burned for creating a heat which is utilized for vaporizing the heavy oils.

An object of the present invention is to provide a device wherein the heavy constituents of a heavy oil are separated from the heavy oil and conducted to a combustion chamber where said heavy constituents are burned, and the heat thereof is utilized for heating the vaporizing chamber into which the heavy oil is initially conducted for vaporizing the remainder of the heavy oil.

A further object of the invention is to provide a device of the above character wherein means is provided for conducting the vaporized heavy oil through the combustion chamber whereby the heat in the combustion chamber may be used for superheating the vaporized heavy oil as it is led to its place of use.

A still further object of the invention is to provide a device of the above character which may be used in conjunction with an explosive engine, and wherein the exhaust gases from the engine are utilized for creating a draft through the combustion chamber.

A still further object of the invention is to provide a device of the above character wherein the vaporizing chamber is provided with an inclined plate at the bottom portion thereon on to which the heavy oil is fed and wherein said vaporizing chamber is so associated with the combustion chamber that the products of combustion are directed against the bottom portion of said plate.

A still further object of the invention is to provide a device of the above character wherein the means for feeding the heavy oil to the vaporizing chamber and on to the inclined plate may be shifted to different positions relative to said inclined plate during the initial installation of the device.

A still further object of the invention is to provide a device of the above character with means whereby the vaporizing chamber may be kept substantially under atmospheric pressure.

A still further object of the invention is to provide a device of the above character wherein means is provided for supplying the superheated vaporized heavy oil with air, whereby a proper fuel mixture is produced for the explosive engine.

These and other objects will in part be obvious and will in part be hereinafter more fully disclosed.

In the drawings which show by way of illustration one embodiment of the invention—

Figure 1 is a side view of a device embodying my improvements;

Fig. 2 is a longitudinal sectional view on the line 2—2 of Fig. 3, and

Fig. 3 is a sectional view on the line 3—3 of Fig. 2.

The invention is directed broadly to a device for vaporizing or gasifying heavy oils. While the device may be used for various purposes, it is particularly adapted for use in connection with an explosive engine, and will be so described in detail hereinafter.

The device includes a vaporizing chamber which is preferably provided with an inclined bottom plate on to which the heavy oil to be vaporized or gasified is fed from a supply pipe which is provided with a suitable control valve. This vaporizing chamber is provided with means for collecting the heavy constituents in the heavy oil which are not readily vaporized. Associated with this vaporizing chamber is a combustion chamber which is preferably placed directly beneath the vaporizing chamber. Means is provided for conducting the heavy constituents of the heavy oil collecting in the vaporizing chamber to this combustion chamber, and a suitable valve is provided for controlling the supply. The heavy constituents as they pass into the combustion chamber are led over suitable plates, which, during the burning of the constituents, become very hot and aid in the vaporizing of these heavy constituents. A suitable wicking is provided to further retain the heavy constituents until they are consumed. The burning of the heavy constituents is for the purpose of heating the vaporizing chamber. Suitable means is provided for causing

a draft through the combustion chamber, and this is preferably obtained by utilizing the exhaust gases from the explosive engine for the purpose. As these heavy constituents are consumed, the entire vaporizing chamber is intensely heated, and therefore, the heavy oils fed on to the inclined bottom plate will be largely vaporized and gasified, and only a small portion of the very heavy constituents will accumulate on the bottom portion of the vaporizing chamber. It is the intention of burning up all of these heavy constituents. To this end, the supply pipe may be shifted relative to the inclined plate in the vaporizing chamber so as to increase or decrease the length of flow of the heavy oil on said inclined plate. This is only done in the initial installation of the device. A suitable low pressure air intake is provided for the combustion chamber. Pipes are provided for conducting the vaporized or gasified heavy oil from the vaporizing chamber to the place of use, and these pipes extend through the combustion chamber so that the vaporized or gasified heavy fuel in the pipes is superheated. Also located in the combustion chamber is a compartment into which the pipes lead. An air supply pipe is also led into this compartment, and a pipe for carrying off the mixed air and gas vapor leads into the compartment. The air pipe is adjustable for controlling the mixture of air with the fuel gas or vapor, and a throttle valve of the usual character may be used for controlling the fuel mixture led to an explosive engine when the device is used for such purpose. Associated with the vaporizing chamber is means for maintaining said vaporizing chamber substantially at atmospheric pressure.

Referring more in detail to the drawings, my improved device for gasifying heavy oils consists of a main casing 1 which may be of any suitable shape or design. Said casing is provided with an inclined partition 2, in the upper portion thereof, which divides the casing into an oil gasifying or vaporizing chamber 3 and combustion chamber 4. This bottom plate 2 of the vaporizing chamber inclines downwardly toward the right side of the device as viewed in Fig. 2. At the lower end of said inclined plate 2 there is an opening through the wall of the casing 1, and a pipe 5 is attached to said opening. Said pipe 5 leads to a receptacle 6 which may be attached to the side wall of the casing.

The heavy oil to be gasified or vaporized is supplied to the vaporizing chamber 3 by a supply pipe 7 which is provided with a suitable valve 8. The top wall of the casing 1 is provided with a series of openings 9, 9. The pipe 7 extends through one of these openings, and the remaining openings are closed by suitable caps 10. The purpose of providing a series of openings is to permit the

shifting of the supply pipe 7 for reasons which will be referred to later. The heavy oil fed through the supply pipe is directed on to the inclined bottom plate 2, and this inclined bottom plate 2 is preferably concave on its upper face so that the stream of heavy oil will run along the center of the plate. As has been stated above, this bottom plate 2 is heated, and in fact, the entire vaporizing chamber is heated. The heat of the plate over which the oil flows and the heat of the chamber will cause the heavy oil to be vaporized or gasified to a great extent. A certain portion of the heavier constituents, however, will collect or accumulate at the bottom end of the inclined bottom plate 2, and will run off through the pipe 5 into the receptacle 6. This receptacle 6 is provided with a vent opening to the atmosphere, indicated at 11. It is also provided with a suitable overflow pipe 12, although when the device is properly set up, the accumulating heavy constituents will all be consumed in the combustion chamber. A pipe 13 leads from this receptacle 6 through the wall 14 of the casing 1. The end 15 of the pipe extending through the wall 14 is directly above plates 16 and 17. These plates are attached to the wall 14 of the casing, and the plate 17 extends to a slightly greater extent into the combustion chamber. The heavy oil passing out of the pipe 13 will flow on to the plate 16, and will spread out on said plate, and will flow off from the end thereof on to the plate 17, and thence on to a porous asbestos wicking 18 during the initial starting of the device. As soon as the combustion is started, then the oil will be consumed on the plates, which will be intensely heated and aid in the vaporizing of the heavy constituents for consumption. The pipe 13 is provided with a hand valve 19 for controlling the supply of the heavy oil constituents to the combustion chamber. Attached to the wall 14 is an air intake pipe 20 through which low pressure air is admitted to the combustion chamber. This pipe may be provided with a branch portion 21, through which a torch may be extended for igniting the heavy oil in the combustion chamber. This pipe may be closed by a plate 22 after the device is started. Attached to the casing 1 is an exhaust pipe 23 for the combustion chamber, and extending into this exhaust pipe 23 is an exhaust pipe 24, which is connected with the exhaust of an explosive engine when the device is used in connection with an explosive engine. The exhaust gases passing from the pipe 24 into and through the pipe 23 will create a draft through the combustion chamber, drawing air in through the pipe 20.

The casing 1 is provided with a cross partition 25 in the combustion chamber, which is preferably cylindrical in shape. This partition forms a compartment 26. There are

two pipes 27, 27, which extend up through the bottom plate 2 and are spaced on opposite sides of the central portion of the bottom plate along which the heavy oil tends to flow. 5 These pipes 27 are also connected with the cross partition 25 and lead into the compartment 26. The pipes 27 extend some distance above the bottom plate and are for the purpose of collecting and drawing off the vaporized or gasified heavy oil in the vaporizing chamber 3. The casing 1 is provided with baffle plates 28, 28, which are so disposed as to direct the heat of combustion across and about the pipes 27 and the lower side of the 10 inclined bottom plate 2 of the vaporizing chamber 3. This causes the pipes 27 to become intensely heated, and the gases or vapors passing therethrough superheated, which greatly increases the efficiency of the 15 fuel mixture when used in a combustion engine.

In order that the fuel gas received into the mixing chamber 26 may be mixed with air, an air supply pipe 29 is provided. This air 25 supply pipe 29 is threaded into the side wall 1 of the casing, and is capable of being adjusted endwise in said side wall. A nut 30 is threaded on to the pipe and locks the pipe in its adjusted positions. An outlet pipe 31 30 extends through the opposite wall of the casing and is of substantially the same dimensions and in alinement with the air pipe 29. The ends of these pipes are spaced from each 35 other in the chamber 26, and the oil gas in the chamber passes into the fuel pipe 31 and is thoroughly mixed with air passing through the pipe 29 and into the mixture pipe 31. The air pipe is preferably of fixed dimensions, and by shifting the air pipe, the amount of 40 oil gas mixed with the air can be varied. The mixture pipe 31, when the device is used in an explosive engine, is provided with a suitable throttle valve.

Associated with the vaporizing chamber is 45 means for maintaining said vaporizing chamber substantially at atmospheric pressure. As shown in the drawings, this is accomplished by a pipe 32 which is in the form of a coil and open at its outer end. It will 50 be understood, of course, that the suction of the engine will draw the air and oil gas mixture from the mixing compartment 26 and will also draw the vaporized or gasified heavy fuel oil from the vaporizing chamber 3. If 55 the demand of the engine is suddenly cut down, so that more vaporized or gasified fuel is provided than the engine needs, then the surplus may pass off into this pipe 32. If 60 there is an over-abundance, it may escape out through the pipe, otherwise some of the oil vapors might condense in the pipe and drain back into the vaporizing chamber. Then again, when the amount of gasified fuel is not 65 sufficient to supply the demand of the engine, due to certain sudden changes in the condi-

tion of operation, air may be drawn in through the pipe 32 and thus prevent the stalling of the engine.

It will be noted that heavy oil has been referred to throughout the description, but it is understood, of course, that by this term we mean oils which are heavier than kerosene. This heavier oil may contain lighter oils, but the object of the invention is to consume and utilize all of the heavy oil, and particularly to utilize the asphaltic constituents in the combustion chamber for creating the heat to aid in the vaporizing or gasifying of all of the remaining portions of the heavy oil for use in an explosive engine.

For easy starting, a small amount of gasoline or other light oil may be directed into the combustion chamber through a pipe 33 and a spark plug may be used for igniting the vapors in the combustion chamber. 80 After the combustion chamber is well heated, then the valve 19 is opened to allow the heavy oil constituents to flow on to the plates 16 and 17. If there should not be a supply of heavy oil constituents, then of course, the valve 8 is opened, so that the heavy oil may run down through into the combustion chamber. 85 As soon as the device is heated to an operating temperature, then the heavy oil which flows on to the inclined plate 2 will be vaporized, and the heavy oil constituents collected and fed to the combustion chamber for maintaining the combustion therein. It 90 will thus be seen that I have provided a device wherein the heavy constituents in the heavy oil are burned, and the heat of combustion is utilized for vaporizing the remaining portions of the heavy oil, and for conditioning the vaporized or gasified heavy oil for use in an explosive engine.

It is obvious, of course, as has been noted, that my improved device may be used for other purposes. It will also be obvious that the details of construction may be greatly varied or modified without departing from the spirit of the invention as set forth in the appended claims.

Having thus described the invention, what I claim as new and desire to secure by Letters-Patent, is—

1. A device for gasifying heavy oils, comprising an oil vaporizing and gasifying chamber having an inclined plate on which the oil to be vaporized is fed, means for collecting the heavy constituents separating from the oil on said inclined plate, a receptacle connected to the collecting means for storing the heavy constituents, a combustion chamber, a valve controlled means for supplying the connected heavy constituents to the combustion chamber, said combustion chamber being disposed relative to said vaporizing chamber so that the burning of the heavy constituents in the combustion chamber will heat the vaporizing chamber, means for sup-

- plying air to the combustion chamber, means for creating a draft through said combustion chamber, pipes extending into the vaporizing chamber to a point above the inclined partition and connected to a compartment located in the combustion chamber but separated therefrom whereby the vaporized heavy oil is led from the vaporizing chamber into said compartment and is further heated and gasified therein, means for leading the heavy vaporized oil from said compartment, and means for mixing air with the heavy vaporized oil after it leaves the vaporizing chamber.
2. A device for gasifying heavy oils, comprising a casing, an inclined partition dividing said casing into an upper oil vaporizing chamber and a lower combustion chamber, a pipe extending through the upper wall of the casing for feeding heavy oil on to the inclined partition, said upper wall having a series of openings whereby said pipe may be shifted and the heavy oil fed onto said inclined partition at different distances from the lower end thereof, means for collecting the heavy constituents separating from the oil on said inclined partition and supplying the same to the combustion chamber for burning, said combustion chamber having an air intake, a cross partition in said combustion chamber forming a compartment, a pipe extending from said compartment through said inclined partition to a point above the same for directing the vaporized heavy oils from the vaporizing chamber into said compartment, means whereby said vaporized oil may be led from said compartment, and means for supplying air to the vaporized oil.

In testimony whereof, I affix my signature.

JAMES WM. INGLETON.
